UNITED STATES PATENT OFFICE.

CHARLES GEORGE JOHNSON, OF SAULT STE. MARIE, MICHIGAN, ASSIGNOR OF ONE-HALF TO NILS LUDEWIC LARSEN, OF SAULT STE. MARIE, MICHIGAN.

LIFE-SAVING BUOY.

1,377,486.

Specification of Letters Patent. Patented May 10, 1921.

Application filed June 8, 1920. Serial No. 387,437.

To all whom it may concern:

Be it known that I, CHARLES GEORGE JOHNSON, a citizen of the United States, residing at Sault Ste. Marie, in the county 5 of Chippewa and State of Michigan, have invented certain new and useful Improvements in Life-Saving Buoys, of which the following is a specification.

The present invention relates to a life 10 saving buoy for ships, and has for its object to provide a device of this character which embodies novel features of construction whereby it will float on the surface of the water and house a number of persons 15 in safety and comparative comfort in the event the ship sinks.

Further objects of the invention are to provide a life saving device of this character which has a strong and durable construction, which is absolutely dependable 20 in its operation and is at all times ready for an emergency, which provides in an adequate manner for the protection and comfort of persons who may be saved by the 25 buoy, and which may also maintain a cable connection with the sunken vessel for the purpose of enabling the same to be located.

With these and other objects in view the invention consists in certain combinations 30 and arrangements of the parts as will more fully appear as the description proceeds, the novel features thereof being pointed out in the appended claims. For a full understanding of the invention reference is to 35 be had to the following description and accompanying drawings, in which:—

Figure 1 is a sectional view through a life saving buoy constructed in accordance with the invention, a portion of the ventilating tower being broken away.

Fig. 2 is an enlarged horizontal sectional view on the line 2—2 of Fig. 1.

Fig. 3 is a top plan view of the device.

Fig. 4 is a horizontal sectional view on 45 the line 4—4 of Fig. 1.

Corresponding and like parts are referred to in the following description and indicated in all of the views of the drawings by like reference characters.

Specifically describing the present embodiment of the invention, the numeral 1 50 designates the middle portion of the sheet metal shell or casing, said middle portion being preferably cylindrical in shape since 55 a body with a circular cross section inher-

ently possesses a great amount of strength and power to resist forces acting upon the exterior thereof. The bottom 2 of the shell is tapered and substantially frusto conical in shape, as is also the top 3. A floor 4 extends transversely across the interior of the shell at the lower end of the cylindrical body portion 1 thereof, and a transverse wall 5 is provided below the floor. The space between the wall 5 and the bottom of the shell is filled with some heavy material such as concrete 6 which operates to maintain the buoy in an upright position and prevent it from becoming top heavy when floating. A water compartment 7 is provided between the floor 4 and the wall 5, said water compartment surrounding a central space 8 which is provided by the upright walls 9.

This space 8 is water tight and has a reel 75 10 housed within the same. Suitable bearings 11 are provided for the reel, and a cable 12 which is connected to the reel extends through a tubular guide member 13 to the exterior of the buoy, said guide member being arranged within the water compartment 7 and connecting the walls thereof. A suitable guide roller 14 is arranged at the inner end of the tube 13 and serves to direct the cable 12 as it is taken in or let out. The 80 opposite end of the cable 12 is intended to be fastened to the ship, so that in the event the ship sinks the cable will unwind from the reel and maintain a connection between the buoy and the ship, thereby enabling the sunken ship to be located. The 85 buoy will, of course, rest loosely upon a suitable cradle or seat provided on the deck of the ship, in the well known manner. This cradle will hold the buoy against lateral 90 displacement under all normal conditions, although the buoy is not held against upward movement, being free to float if the vessel sinks.

Provision may also be made for controlling the reel 10 from the living compartment within the upper portion of the hollow buoy. A vertical shaft 15 is shown as extending downwardly through the floor 4, the lower end of the shaft being geared at 105 16 to the reel, while the upper end thereof is provided with a handle 17. The stuffing box 18 provides a water tight bearing in the floor 4, so that there is no danger of water entering the living compartment of 110

the buoy through the shaft bearing. A second shaft 19 is also shown extending through the floor 4, the lower end of the shaft having an operative connection with 5 a brake 20, while the upper end thereof is provided with a handle 21. A brake means is thus provided for controlling the reel, and there is also a positive means for rotating the reel in either direction should this 10 become necessary or desirable.

The inclined sides of the top 3 are provided with a pair of man holes 22 each of which has an outer glass trap door 23, and preferably an inner solid metal door 23' in 15 the event the outer door is broken by accident, all of said doors being constructed to provide a water tight closure when closed. The flat upper end of the top is provided with a series of deck lights 24, and a ventilating tube or tower 25 extends centrally through the top. An upright shaft 26 is arranged axially within the ventilating tube 25, being maintained in position by spiders 27, and being provided at its upper end 25 with a cap 28 for the ventilating tube 25. The lower end of the said shaft is provided with a crank handle 29, and the shaft has a threaded engagement 30 with one of the spiders 27 so that it is moved longitudinally 30 when it is rotated by the crank handle. The cap 28 can thus be raised or lowered and lifted above the ventilating tube or brought into engagement therewith. A gasket 31 on the cap is adapted to engage a corresponding seat at the upper extremity of the ventilating tube to insure a water tight joint when the cap is closed. Arranged above the cap is a cage 32 within which a suitable signal light may be placed. The interior of 35 the buoy provides a living compartment to which access is had through the man holes 22. An annular seat 33 extends around the living compartment just above the floor 4, the back of the seat being shown as provided by a series of annular strips 34 which 40 are secured to an inner wall 35. This inner wall is spaced from the outer wall of the buoy, thereby providing an air space between the members which prevents sudden 45 changes of temperature from being transmitted through the walls of the buoy to the seat. The occupants of the buoy are thus 50 protected against extreme heat or cold. The upper edge of the inner wall 35 is riveted at 36 to the outer shell of the buoy and then deflected inwardly to provide a flange 37 which is perforated at intervals, as indicated at 38. If necessary, straps can be 55 suitably attached to this perforated flange 37 for the purpose of holding the occupants of the buoy in proper position on the seat. The floor 4 is provided with a trap door 39 arranged over the water compartment 7, said compartment being adapted to contain 60 a supply of fresh water when the life sav-

ing device is used upon ocean going vessels. A faucet 40 is provided under the seat for drawing water as needed from the exterior of the buoy, and suitable toilet facilities are provided as indicated at 41. The exterior 70 of the buoy is preferably provided with one or more rails 42 to which any unfortunates may cling who may not be able to get into the interior of the buoy. These rails would also enable the buoy to be used as a life 75 saver in the event the vessel should sink so quickly that there was no opportunity to enter the buoy at the time.

Having thus described my invention, what I claim as new and desire to secure by Letters Patent is:—

1. A life saving buoy including a hollow shell inclosing a living compartment, walls providing a closed chamber within the shell separate from the living compartment, a reel mounted within the chamber, a tubular cable guide extending from the chamber to the exterior of the shell, a cable extending through the guide and attached to the reel, and control means for the reel operable 90 from the living compartment.

2. A life saving buoy including a hollow shell inclosing a living compartment, a floor extending transversely across the shell and providing a water compartment below the 95 same, walls providing a separate closed chamber under the floor and within the water compartment, a reel mounted within the chamber, a tubular cable guide extending from the chamber to the exterior of the 100 shell, a cable connected to the reel and extending through the guide, and control means for the reel operable from the living compartment.

3. A life saving buoy including a hollow 105 shell, inclosing a living compartment, a transverse floor extending across the shell at the bottom of the living compartment, a reel mounted within the shell under the floor, a tubular cable guide extending to the 110 exterior of the shell, a cable extending through the guide and connected to the reel, a shaft extending through the floor and geared to the reel for operating the same, a second shaft extending through the floor, 115 and a brake operable by the second shaft.

4. A life saving buoy including a hollow shell, a pair of spaced transverse walls extending across the lower end of the shell, the upper wall providing a floor for a living 120 compartment above the same and a water compartment being provided between the two walls, a weight confined under the lower wall, upright walls connecting the two transverse walls and providing a separate 125 closed chamber surrounded by the water compartment, a reel mounted within the chamber, a tubular cable guide extending from the chamber to the outside of the shell, a cable extending through the guide and 130

connected to the reel, a shaft extending through the floor into the chamber and operable from the living compartment, and means associated with the shaft for controlling the reel.

5. A life saving buoy including a hollow shell inclosing a living compartment, a pair of spaced transverse walls extending across the lower end of the shell below the living compartment, a water compartment being provided between the two transverse walls, a permanent weight confined between the lower wall and the bottom of the shell, upright walls connecting the two transverse walls and providing a separate chamber within the water compartment, a reel mounted within the separate chamber, and a cable operatively associated with the reel and extending to the exterior of the shell.
- 10 6. A life saving buoy including a hollow shell inclosing a living compartment, walls providing an interior closed chamber within the hollow shell, a tubular guide extend-

ing from the walls of the chamber through the exterior of the shell, a reel mounted 25 within the shell, a cable extending through the tubular guide and connected to the reel, shafts extending through the walls of the chamber and operable from the living compartment, gearing controlled by one of the 30 shafts for operating the reel, and a brake controlled by the other shaft for controlling the reel.

7. A life saving buoy including a hollow shell inclosing a living compartment, walls 35 providing a separate closed chamber arranged within the hollow shell and spaced from the walls thereof, a reel within the said chamber, a cable connected to the reel and extending through the buoy to the exterior 40 thereof, a shaft extending through the walls of the chamber and operable from the living compartment, and means actuated by the shaft for controlling the reel.

In testimony whereof I affix my signature. 45
CHARLES GEORGE JOHNSON.
